UNITED STATES PATENT OFFICE.

FRANCIS F. BRAILLARD, OF BROOKLYN, NEW YORK.

LOCK FOR SATCHELS, &c.

SPECIFICATION forming part of Letters Patent No. 397,487, dated February 12, 1889.

Application filed January 3, 1889. Serial No. 295,314. (No model.)

To all whom it may concern:

Be it known that I, FRANCIS F. BRAILLARD, of Brooklyn, New York, have invented an Improved Lock for Satchels, &c., of which the following is a specification.

This invention relates to a lock for satchels, chatelaine bags, and other articles, which is so constructed that it will not be apt to become automatically opened by accidental contact ⁵ with the push-button or by a weakening of the spring. The lock is constructed to be opened by a freely-swinging pendant, which operates the bolt only after being swung up to such an extent as to bring a nose on the ¹⁰ pendant into contact with the bolt-carrying plate or slide.

The invention consists in the various features of improvement, more fully pointed out in the claims.

¹⁵ In the accompanying drawings, Figure 1 is a rear view of the lock, showing it on a bag-frame. Fig. 2 is a front view of the lock, exposing the side ordinarily covered by the bag-frame. Fig. 3 is a front view of the bag-frame, showing the outline of the lock in dotted lines. Fig. 4 is a vertical transverse central section through the lock, showing it closed. Fig. 5 is a similar section showing it open.

²⁰ The letters *a a'* represent the two jaws of a bag or other device to be locked together. The jaw *a'* carries the slotted plate *b*, which is to be engaged by the bolt or catch upon the other jaw, as usual. The jaw *a* is provided ²⁵ on its face with a pair of outwardly-projecting posts, *c c'*, upon which there is hung by pintle *d'* a ring or other pendant, *d*, free to swing back and forth, and which may be used for pulling the jaws apart after the catch has

³⁰ been opened. The ring *d* is provided at its upper end with a cam or nose, *e*, that projects through a slot of jaw *a* and into the lock-case *f*, riveted to the rear of jaw *a*.

Within the lock-case *f* there is placed a slide, ³⁵ *i*, having lateral extensions or shoulders *i'*, that guide the slide within the case. To the slide *i* there is affixed the bolt, catch, or hook *j*, that projects out of the slotted back plate, *f'*, of case *f*, and that is free to engage slotted ⁴⁰ plate *b* on jaw *a'*. Between the shoulders *i'*

of slide *i* and the bottom of case *f* there is placed, at each side of the slide, a spiral spring, *k*. These spiral springs, placed in the manner described, will not become worn or stiff for a long time.

⁵⁵ The slide *i* has a long slot, *i'*, and this slot is placed opposite the slot of jaw *a* and opposite the nose *e* of pendant *d*, so that said nose may operate the slide in the manner hereinafter described.

⁶⁰ The operation of the lock will be readily understood. When the lock is closed, as in Fig. 4, the springs *k* are distended and have thrown the slide *i* upward, so that the hook *j* engages plate *b*. In this position the pendant *d*, by its weight, causes the nose *e* to stand in its most upright position, and thus the nose is entirely withdrawn from the lock-case. When it is desired to open the lock, the pendant is swung upward. During the first part ⁶⁵ of its motion it will not affect the lock in any manner. It will simply cause the nose *e* to enter slot *i'*. As soon as the nose has been brought into contact with the lower edge of the slot, and as the pressure is continued, the ⁷⁰ nose will draw the slide *i* down against the action of springs *k*, thus opening the lock, Fig. 5. As the pendant is now released, the nose *e* will automatically withdraw from the lock-case and resume the position shown in ⁷⁵ Fig. 4. To close the lock it is only necessary to press the jaws *a a'* together.

⁸⁰ It will be seen that the ordinary vibrations of pendant *d* will not open the lock. Not until the pendant has been pressed upward ⁸⁵ with sufficient force to move the slide by means of the nose will the catch be released from plate *b*.

What I claim is—

⁹⁰ 1. The combination of a slotted jaw with a vibrating pendant that has a nose passing through said slotted jaw, and with a slide carrying the locking-catch and adapted to be engaged by the nose, substantially as specified.

⁹⁵ 2. The combination of slotted jaw *a* with outwardly-projecting posts *c c'*, carrying a swinging pendant, *d*, having nose *e*, and with slide *i*, having catch *j* and slot *i'*, the nose *e* passing through slotted jaw *a* and into en- ¹⁰⁰

gagement with slot i^2 , substantially as specified.

3. The combination of slotted jaw a with outwardly-projecting posts c , carrying pendant d , that has nose e , and with the slide i , having shoulders i' and slot i^2 , and with the catch j , secured to the slide, and with the

spiral springs k , placed between shoulders i' and the bottom of the lock-case, substantially as specified.

FRANCIS F. BRAILLARD.
